United States Patent Office

Des. 191,340
Patented Sept. 12, 1961

191,340

PEN

Jack Hillel Shaw, London, England, assignor to Penparts
Limited, London, England

Filed Oct. 27, 1960, Ser. No. 62,637

Claims priority, application Great Britain June 23, 1960

Term of patent 3½ years

(Cl. D74—17)

FIG. 1 is a rear elevational view of a pen showing my new design;

FIG. 2 is a side elevational view thereof, the side opposite thereto being similar in appearance;

FIG. 3 is a front elevational view;

FIG. 4 is a top plan view of FIG. 1; and

FIG. 5 is a bottom plan view of FIG. 3.

I claim:

The ornamental design for a pen substantially as shown and described.
